CONVERSION AND COKING OF
HYDROCARBONS

Alfred Fisher, Chicago, Ill., assignor to Universal
Oil Products Company, Chicago, Ill., a corpo-
ration of Delaware

Application June 2, 1933, Serial No. 674,001

9 Claims. (Cl. 196—49)

This invention particularly refers to an improved process and apparatus for the conversion and coking of mixtures of hydrocarbon oil and solid or semi-solid carbonaceous material such 5 as coal, peat, lignite, oil shale and the like wherein intermediate liquid products of the process are subjected to further conversion under independently controlled more severe conversion conditions in the same system while the heavy liquid 10 products of the conversion and coking operations are returned for further treatment with the charging stock.

One specific embodiment of the present invention may comprise subjecting a mixture of hydrocarbon oil and finely divided carbonaceous material to mild conversion in a heating coil under non-coking conditions, introducing the heated material into a plurality of alternately operated coking ovens wherein the residual conversion products are reduced to coke and the coke is substantially devolatilized by introducing the oil onto a highly heated surface, subjecting the vaporous products from the coking ovens to fractionation whereby they are separated into fractionated vapors of the desired end-boiling point, intermediate condensate and higher boiling liquid products including tars and similar high coke-forming materials, returning the latter to further treatment, together with the charging stock, subjecting the fractionated vapors to condensation, collecting and separating the resulting distillate and gas, subjecting the intermediate condensate to further conversion under independently controlled more severe conversion conditions, separating the resulting vaporous and residual liquid conversion products, returning the latter to further treatment, together with the charging stock, subjecting the vaporous conversion products to fractionation whereby their insufficiently converted components are condensed as reflux condensate, returning reflux condensate to further treatment, together with said intermediate condensate from the first described cracking and coking operation, subjecting the fractionated vaporous conversion products of the desired end-boiling point to condensation and collecting and separating the resulting distillate and gas.

The features and advantages of the present invention will be more apparent with reference to the accompanying diagrammatic drawing which illustrates one specific form of apparatus in which the process of the present invention may be accomplished. The drawing and the following description thereof embodies several modi-

fications of the specific embodiment of the invention above described which are within the scope of the present invention.

Referring to the drawing, raw oil charging stock, comprising any desired hydrocarbon oil 5 such as crude petroleum, petroleum residue, fuel oil or the like, including such oils as coal tar, pitches and other heavy oils, is supplied through line 1 and valve 2 to pump 3 by means of which it is fed through line 4 and valve 5 into mixing tank 6 wherein it may be commingled and intimately mixed with other ingredients of the combined feed for the process. Coal or other suitable solid or semi-solid carbonaceous material is added to the mixing tank, preferably in finely 15 divided form and in regulated amounts relative to the raw oil, through a hopper or other suitable charging device 7 of any suitable form. Mixing tank 6 is preferably equipped with a stirring device 8 of any suitable form by means of 20 which the carbonaceous material is finely dispersed throughout the body of the oil and the ingredients of the combined feed are maintained in a thoroughly commingled state. Other oils from within the system may be added to the 25 materials in the mixing tank to make up the total combined feed for the process, as will be later more fully described, and the commingled materials are withdrawn from the mixing tank through line 9 and valve 10 to pump 11 by means 30 of which they are fed through line 12 and valve 13 to heating coil 14. When the charging stock is of a heavy viscous nature it may be necessary to heat the liquid charging stock and/or the combined feed by means of steam jacketed lines 35 or a steam jacketed mixing tank or in any other suitable well known manner, not illustrated in the drawing, in order to facilitate the handling of this material. When desired, heat for this purpose may be recovered from within the sys- 40 tem by means of heat exchangers or the like, not illustrated in the drawing.

Heating coil 14 is located within a furnace 15 of any suitable form by means of which the combined feed passing therethrough is heated 45 quickly to the desired conversion temperature, preferably at a substantial superatmospheric pressure, without allowing sufficient conversion time in the heating coil to cause any detrimental formation and deposition of coke in this zone, 50 a high rate of heating being maintained in furnace 15 and a high oil velocity being maintained through heating coil 14 for this purpose. The heated materials pass from heating coil 14 through line 16 and valve 17 and are introduced 55

into the coking oven 23, through lines 24, 24' and 24'', controlled by the respective valves, 25, 25' and 25''.

Coking oven 23 preferably comprises a plurality of coking chambers 26, 26' and 26'' which may be alternately operated, cleaned and prepared for further operation in order to render the process continuous. It will be understood that any number of similar coking chambers may be employed, although only three are illustrated in the drawing. Each of the coking chambers has a floor 27, preferably constructed of suitable refractory high heat conductive material such as silicon carbide, fused aluminum oxide, aluminum silicate and the like, heated to a high temperature from beneath by means of the combustion of any suitable type of fuel in combustion zones 28. The heated oil from heating coil 14 is directed onto the highly heated floor of one or more of the coking chambers whereby the oil is coked and the coke is allowed to accumulate in a relatively thin layer to a depth of approximately 6 inches or less over the highly heated floor, following which heating may when desired be continued for a time to devolatilize the coke to the desired degree, during which the oil is diverted to another coking chamber, and finally the layer of devolatilized coke is removed, by means of an hydraulic ram or in any other suitable well known manner, following which the chamber is prepared for further operation. Vaporous products are withdrawn from the coking chambers through lines 29, 29' and 29'' controlled by valves 30, 30' and 30'', respectively, and pass into fractionator 31 which, in the case here illustrated, also serves as a vaporizing and tar separating zone.

The vaporous products supplied to fractionator 31 may be separated into three major components comprising light fractionated vapors of the desired end-boiling point, intermediate condensates and higher boiling liquids, the latter including any tars or similar high coke-forming materials or, when desired, the total reflux condensate comprising the intermediate condensates and higher boiling liquids may be recovered without dividing it into low-boiling and high-boiling fractions.

Fractionated vapors of the desired end-boiling point pass from the upper portion of fractionator 31 through line 37 and valve 38 to condenser 39 wherein they are subjected to condensation and cooling and from which the resulting distillate and gas passes through line 40 and valve 41 to collection and separation in receiver 42. Undecondensable gas may be released from the receiver through line 43 and valve 44. Distillate may be withdrawn from this zone to storage or to any desired further treatment through line 45 and valve 46.

It is within the scope of the present invention to employ substantially atmospheric, sub-atmospheric or a low superatmospheric pressure in the coking oven. In case sub-atmospheric pressure is employed in this zone it is also preferably employed in the succeeding fractionating, condensing and collecting equipment of this portion of the system, in order to avoid pumping or compression of the vaporous products from the coking oven at high temperature, the sub-atmospheric pressure being controlled by means of a vacuum pump 49 which withdraws gas from receiver 42 through line 47 and valve 48, discharging it through line 50 and valve 51, from which it may pass through suitable scrubbing equipment, not shown, or direct to a gas holder, not shown, or elsewhere, as desired.

When intermediate condensates are recovered from fractionator 31 this material which is of a higher boiling nature than the overhead vaporous product from the fractionator and of lower boiling nature than the high coke-forming liquids removed from the lower portion of the fractionator may be withdrawn as one or a plurality of side streams from the fractionator, for example, through line 52 and valve 53 to pump 54 by means of which these intermediate fractions are fed through line 55 and valve 56 and may pass, all or in part, either through valve 57 in this line into fractionator 58 or, all or in part, from line 55 through line 59, valve 60 and line 65 into heating coil 70. It will be understood that, when desired, the intermediate condensate from fractionator 31 may be subjected to reboiling in a suitable side stripper column or in any well known manner, not illustrated, in order to free it of entrained gas and/or desirable low-boiling fractions within the range of the overhead product from fractionator 31.

Depending upon the method of the operation chosen, the liquid withdrawn from the lower portion of fractionator 31 through line 32 and valve 33 to pump 34 may comprise the total condensate removed from the vapors by fractionation in this zone or only its high-boiling fractions including tars and similar high coke-forming materials. In either case this material is fed by means of pump 34 through line 35 and may pass, all or in part, either through line 36, valve 69, line 55 and valve 57 into fractionator 58 or through line 71, valve 72 and line 12 to heating coil 14 for further conversion together with the charging stock or, when desired, instead of passing direct to heating coil 14 the oil from line 71 may pass through line 73 and valve 74 into mixing tank 6 to commingle therein with the charging stock mixture, prior to its passage to heating coil 14.

The condensate supplied from fractionator 31 to fractionator 58 comprises either all or a portion of the total liquids recovered from the vapors in fractionator 31 or a portion or all of only the intermediate condensates from fractionator 31, as already described. This material serves as a refluxing medium to assist fractionation of the vaporous conversion products supplied to fractionator 58, as will be later more fully described, and, when desired, the oil may be cooled to any desired degree, prior to its introduction into fractionator 58 by well known means, not shown in the drawing. The total material supplied to fractionator 58, including both vaporous conversion products and liquid from fractionator 31, may be separated, after the removal of low-boiling vaporous products comprising the overhead stream from the fractionator, into low-boiling and high-boiling condensate fractions or, when desired, the total liquid recovered from the materials supplied to fractionator 58 may be removed therefrom without separation. In the latter case this material is withdrawn from the lower portion of fractionator 58 through line 61 and valve 62 to pump 63 by means of which it is fed through line 64, line 65 and valve 66 to further conversion in heating coil 70. Preferably this method of operation is not employed except when only intermediate condensates from fractionator 31 are supplied to fractionator 58 in order to avoid the return of any tars or similar high coke-forming materials from fractionator 31 to heating coil 70.

In case only high-boiling fractions of the liquid recovered from fractionator 58 are supplied to pump 63 this material is preferably returned

through line 64, line 67, valve 68 and line 12 to heating coil 14 for further conversion or it may be diverted, all or in part, from line 67 through line 75 and valve 76 into mixing tank 6 to commingle with the charging stock mixture, prior to its introduction into heating coil 14.

When low-boiling fractions of the liquids recovered from fractionator 58 are separated from the higher boiling fractions in this zone they may be removed from the fractionator as one or a plurality of side streams, for example, through line 77 and valve 78 to pump 79, being reboiled, when desired, by well known means, not shown in the drawing, for the purpose of freeing this material from entrained gases and any low-boiling fractions within the range of the desired overhead product from fractionator 58. The low-boiling oils thus supplied to pump 79 are returned through line 80, valve 81, line 59 and line 65 to further conversion in heating coil 70.

A furnace 82 of any suitable form, enclosing heating coil 70, supplies the required heat to the oil passing therethrough to bring it to the desired conversion temperature, preferably at a substantial superatmospheric pressure, and the heated oil is discharged through line 83 and valve 84 into reaction chamber 85.

Chamber 85 is also preferably maintained at a substantial superatmospheric pressure and, although not illustrated in the drawing, is preferably well insulated to prevent the excessive loss of heat therefrom so that conversion of the heated oil from heating coil 70, and particularly its vaporous components, may continue in this zone. In the case here illustrated, both vaporous and liquid conversion products are withdrawn from the lower portion of chamber 85 through line 86 and valve 87 and are introduced into vaporizing and separating chamber 88.

Chamber 88 is preferably operated at a substantially reduced pressure relative to that employed in chamber 85, by means of which further vaporization of the liquid conversion products supplied to this zone is accomplished. Rough fractionating means, for example, such as baffles indicated at 89, may be employed, when desired, in the upper portion of chamber 88 for the purpose of removing entrained heavy liquids from the vaporous conversion products, prior to their introduction into fractionator 58.

Residual liquid conversion products remaining unvaporized in chamber 88 are withdrawn therefrom through line 90 and valve 91 to pump 92, by means of which they may be returned through line 93, valve 94 and line 12 to heating coil 14 or they may pass, all or in part, through line 95 and valve 96 into mixing tank 6, to commingle therein with the other materials supplied to this zone and form a component of the combined feed supplied, as already described, to heating coil 14.

When liquids are supplied from within the system, as already described, to mixing tank 6 they may, when desired, be cooled by well known means, not shown in the drawing, prior to their introduction into this zone. However, when it is desired to conserve the heat remaining in these products and in case it is not desirable to supply them direct to heating coil 14, as has been previously described, mixing tank 6 may be operated at substantial super-atmospheric pressure in order to minimize vaporization in this zone and is preferably well insulated to conserve heat or may be provided with a suitable steam jacket, not shown. In case the mixing tank is

operated at superatmospheric pressure a suitable valve 97 may be provided beneath hopper 7 and the tank is preferably provided with a vent 98 controlled by valve 99 through which any incidental vapors evolved from the hot material in the mixing tank may pass to the fractionator or elsewhere, as desired.

Vaporous conversion products pass from vaporizing chamber 88 through line 100 and valve 101 to fractionation in fractionator 58, wherein their insufficiently converted components are condensed as reflux condensate, to be returned, as already described, to heating coil 70 for further conversion or separated into low-boiling and high-boiling fractions, together with the condensate supplied to this zone from fractionator 31, and subjected to selected further treatment, as already described. Fractionated vapors of the desired end-boiling point pass from the upper portion of fractionator 58 through line 102 and valve 103 to be subjected to condensation in condenser 104. The resulting distillate and gas passes from the condenser through line 105 and valve 106 to collection and separation in receiver 107. Uncondensable gas may be released from the receiver through line 108 and valve 109. Distillate may be withdrawn from the receiver through line 110 and valve 111 to storage or further treatment, as desired. A portion of the distillate collecting in receiver 107 may, when desired, be recirculated by well known means, not shown in the drawing, to the upper portion of fractionator 58 for the purpose of assisting cooling and fractionation in this zone, whereby to maintain the desired vapor outlet temperature and control the end-boiling point of the overhead product from the fractionator. In the same manner distillate from receiver 42 may be recirculated as cooling and refluxing medium to the upper portion of fractionator 31, by well known means not illustrated.

It will be understood that various other modifications may be made to the specific embodiment of the invention above described and that apparatus other than the specific form illustrated may be employed without departing from the scope of the present invention. For example, instead of withdrawing both vaporous and liquid conversion products from chamber 85 in commingled state they may be separately withdrawn from this zone, the liquid passing either to mixing tank 6 or direct to heating coil 14 or being first subjected to further vaporization in a zone of reduced pressure, such as chamber 88 while the vaporous conversion products separately withdrawn from the reaction chamber may also be introduced, all or in part, into the vaporizing chamber at any desired point, when such a zone is employed, or they may pass, all or in part, direct to fractionator 58. For the sake of simplicity the connections required for such optional operations are not illustrated in the drawing, but those skilled in the art can make such connections quickly. It will also be understood that the optional methods of operation described are not to be considered equivalent but may be selected to suit specific requirements.

In an apparatus such as illustrated and above described, the range of suitable operating conditions may be approximately as follows: The conversion temperature employed at the outlet from the heating coil to which the combined feed is supplied may range, for example, from 800 to 900° F., and preferably a substantial super-atmospheric pressure within the range of 100 to 500

pounds, or thereabouts, per square inch is employed at this point in the system. Substantially atmospheric, sub-atmospheric or a low superatmospheric pressure not in excess of 100 pounds, or thereabouts, per square inch is preferred in the coking ovens and the pressure employed in the coking zone may be substantially equalized in the succeeding fractionating, condensing and collecting equipment of this portion of the system. Coking temperatures employed may range from 950 to 1200° F., or thereabouts, and the coke produced may be further heated, when desired, to a temperature up to 1600° F., or more, for the purpose of devolatilizing the same. The second heating coil of the system to which intermediate condensates from the first described cracking and coking operations and all or a selected portion of the reflux condensate from the second cracking operation are supplied may utilize a conversion temperature, measured at the outlet therefrom, within the range of 900 to 1050° F., or thereabouts, preferably with a substantial superatmospheric pressure, measured at this point, of from 200 to 800 pounds, or more, per square inch. Any desired pressure within substantially this same range may be employed in the reaction chamber but is preferably reduced in the vaporizing chamber to a pressure of from 100 pounds, or thereabouts, per square inch to substantially atmospheric. The pressure employed in the vaporizing chamber may be either substantially equalized or somewhat reduced in the succeeding fractionating, condensing and collecting portions of the system.

As a specific example of the operation of the process of the present invention, the raw oil charging stock to be treated comprises a mixture of about two parts by weight of pulverized coal of high volatility to one part of coal-tar. Heavy liquids from the separating and fractionating column of the coking system and residual liquid from the vaporizing chamber of the second cracking stage of the process are admixed with the charging stock in an amount approximately equivalent, by weight, to the coal-tar, so that the total combined feed supplied to the first cracking coil comprises about equal parts by weight of coal and oil. A conversion temperature of approximately 890° F., is employed at the outlet from the heating coil to which this material is supplied, a superatmospheric pressure of approximately 200 pounds per square inch being employed at this point in the system. The heated products are introduced into the coking ovens wherein the non-vaporous residue is reduced to coke at a temperature of approximately 1100° F. A slight subatmospheric pressure is employed in the coking zone and in the succeeding fractionating, condensing and collecting portions of the system. A temperature of approximately 300° F. is maintained at the outlet from the fractionator of the coking system so that a motor fuel product of slightly over 300° F., end-boiling point is recovered from this portion of the system. Intermediate condensates from the fractionator of the coking system, comprising materials boiling above the end-boiling point of the overhead product from the fractionator and up to approximately 600° F., are supplied, together with reflux condensate from the fractionator of the second cracking stage of the process, to the heating coil of this portion of the system wherein the oil is subjected to an outlet temperature of approximately 935° F., at a superatmospheric pressure of approximately 400 pounds per square inch. This pressure is

substantially equalized in the reaction chamber and a reduced pressure of approximately, 50 pounds per square inch is employed in the vaporizing chamber and succeeding fractionating, condensing and collecting equipment of this portion of the system.

An operation of the character above described may produce, per ton of charging stock, about 1320 pounds of coke of low volatility, about 40 gallons of motor fuel of high anti-knock value and about 20% by weight of gas suitable for use as fuel.

I claim as my invention:

1. A process for the pyrolytic conversion and coking of a charging stock mixture of finely divided carbonaceous material in hydrocarbon oil which comprises subjecting the mixture to elevated temperature under non-coking conditions, introducing the heated products into a coking zone wherein the residue is coked in a relatively thin layer upon a highly heated surface, subjecting the vaporous products from the coking zone to fractionation whereby their fractions boiling above the range of the desired final light distillate product are condensed as intermediate liquid products, subjecting the fractionated vapors to condensation, returning high boiling components of said intermediate liquid products of the coking operation for further treatment with the charging stock mixture, simultaneously subjecting selected lower boiling components of said intermediate liquid products of the coking operation to conversion under independently controlled conditions, separating the resulting vaporous and residual liquid conversion products, returning the residual liquid for further treatment with the charging stock mixture, subjecting the vaporous conversion products to fractionation whereby their insufficiently converted components are condensed as reflux condensate, subjecting fractionated vapors of the desired end-boiling point to condensation, and returning the reflux condensate for further treatment in the same system.

2. A process as defined in claim 1 further characterized in that said reflux condensate from the cracking operation is returned for further conversion, together with said selected low-boiling fractions of the intermediate liquid products from the coking operation.

3. A process as defined in claim 1 further characterized in that said reflux condensate from the cracking operation is returned for further treatment with the charging stock mixture.

4. A process as defined in claim 1 further characterized in that selected low-boiling fractions of said reflux condensate from the cracking operation are returned for further conversion, together with said selected low-boiling fractions of the intermediate liquid products from the coking operation.

5. A process as defined in claim 1 further characterized in that selected low-boiling fractions of said reflux condensate from the cracking operation are returned for further conversion, together with said selected low-boiling fractions of the intermediate liquid products from the coking operation, higher boiling fractions of said reflux condensate being returned for further treatment with the charging stock mixture.

6. A process for the pyrolytic conversion and coking of mixtures of finely divided solid carbonaceous material in hydrocarbon oil which comprises subjecting said mixture to elevated temperature under non-coking conditions in a heating coil, introducing the heated products into

5 a coking oven wherein the residue is coked in a relatively thin layer on a highly heated surface, introducing vaporous products from the coking oven into a fractionator and tar separator 5 wherein they are separated into low-boiling fractionated vapors which are subjected to condensation, intermediate condensate and higher boiling liquids, returning the latter to said coil for further treatment with the charging stock mixture, simultaneously subjecting said intermediate condensate to conversion under independently controlled conditions of elevated temperature and 10 superatmospheric pressure in a separate heating coil and communicating reaction chamber, 15 separating the resulting vaporous and residual liquid conversion products, returning the residual liquid for further treatment with the charging stock mixture, subjecting vaporous conversion products to fractionation whereby their insufficiently converted components are condensed as 20 reflux condensate and separated into selected low-boiling and higher boiling fractions, and sub-

jecting the fractionated vapors to condensation.

7. A process of the character defined in claim 6 wherein said low-boiling fractions of the reflux condensate from the cracking operation are returned to the last mentioned heating coil for 5 further conversion.

8. A process of the character defined in claim 6 wherein said high-boiling fractions of the reflux condensate from the cracking operation are returned with the charging stock mixture for 10 further treatment in the first mentioned heating coil.

9. A process of the character defined in claim 6 wherein said high-boiling fractions of the reflux condensate from the cracking operation are 15 returned with the charging stock mixture for further treatment in the first mentioned heating coil and said low-boiling fractions of the reflux condensate from the cracking operation are returned to the last mentioned heating coil 20 for further conversion.

ALFRED FISHER.
